UNITED STATES PATENT OFFICE.

JOSEPH P. TUTTLE, OF ONONDAGA VALLEY, NEW YORK.

STEAM-BOILER FURNACE.

SPECIFICATION forming part of Letters Patent No. 323,375, dated July 28, 1885.

Application filed November 10, 1884. (No model.)

To all whom it may concern:

Be it known that I, JOSEPH P. TUTTLE, of Onondaga Valley, in the county of Onondaga and State of New York, have invented certain new and useful Improvements in Steam-Boiler Furnaces; and I do hereby declare that the following is a full, clear, and exact description thereof, reference being had to the accompanying drawings, and to the letters of reference marked thereon, which form part of this specification, in which—

Figure 1 is a longitudinal section taken vertically through a horizontal steam boiler and furnace, showing my smoke-consuming devices applied to it. Fig. 2 is a front elevation of the same with the front plates removed. Fig. 3 is a top view of my heat-retainer. Fig. 4 is a bottom view of the same. Fig. 5 is a longitudinal section taken centrally through the retainer.

This invention relates to means for consuming smoke in steam-boiler furnaces which are especially designed for burning soft or bituminous coal; and it consists, first, in a novel retainer arranged in the smoke-box, and designed for arresting the heated products of combustion in said box long enough to effect perfect combustion of the carbonaceous matter and the gases; second, in means for facilitating combustion in the fire-chamber and directing the heated gases about the entire surface of the boiler-shell, which is inclosed in the furnace-walls, all of which will be fully understood from the following description, when taken in connection with the annexed drawings.

A A designate the fire-brick furnace-walls, and B a cylindrical boiler mounted therein and constructed with flues a a, secured to heads b b in the usual well-known manner of making a return-flue boiler. C designates the ash-pit of the furnace; D, the fire chamber above the grate; E the contracted flue beneath the boiler, formed by the bridge wall F; E', the ascending flue at the rear end of the boiler; G, the smoke-box at the front end of the boiler, and G' the uptake. All of the parts above-described are old and well known.

The front part, b', of the bridge-wall inclines forward and downward to a point level with the grate, and at the highest part of this inclined plane I apply a pipe, H, which is curved

laterally nearly concentric to the boiler above it. This pipe is provided with numerous small perforations, which are directed forward for the purpose of injecting highly-heated steam over the bed of incandescent fuel on the grate, which steam will furnish a free supply of oxygen gas, which will combine with the gaseous products of combustion and form carbonic-oxide and carbonic-acid gases. The perforated injecting-pipe H communicates with pipes H' H', which are located along the sides, inside, of the furnace-walls A A, which pipes are formed into coils c c for the purpose of greatly increasing the heating capacity of the pipes. The pipes H' H' are carried up from the fire-chamber of the furnace and united to a horizontal pipe, H², which extends across the smoke-box G, where it receives additional heat from the products of combustion on their way to and through a heat arrester and retainer, which will be hereinafter described. The cross-pipe H² communicates by means of a pipe or hose, H³, with a water-forcing engine or with a suitable head of water, the supply of which can be regulated, according to the amount of fire-surface and the heat required, by means of a cock, d, applied to the pipe or hose H³.

J designates a rectangular flanged frame, which is supported horizontally in the smoke-box G by means of side ledges, f f. This frame is arranged above the horizontal plane of the highest series of boiler-flues, and it is removable from the smoke-box through a man-hole at the front end of the steam-boiler. In this frame J is supported my improved heat-retainer and arrester of any light carbonaceous matter and ash on their way to the uptake. This heat-retainer is preferably made of two or more sections, as shown, each section being constructed as follows: K K designate two plates, which are secured together by means of angular bridges L L, and constructed with convex inner edges, l l, with a space between them which diverges from the middle of their length to their ends, as shown in Fig. 4 of the drawings. The feet of the bridges L L are riveted to the plates K K, and to the tops of the bridges a plate, N, is riveted, which plate is parallel to the plates K K, and it is constructed with concave or scalloped edges n n, as shown in Fig. 3. The course of the ascending currents through the retainer is indicated

by the arrows in Fig. 1. It will be seen that the gaseous products first pass between the bottom plates, K K, then strike the plate N, and are then deflected horizontally forward and backward over the bottom plates. By curving the edges of the plates, as described, the ascending heated products will be uniformly distributed laterally in the smoke-box.

This device just described is not only a heat-retainer, but, by reason of its becoming intensely hot, it will materially aid in the process of combustion in the smoke-box, and also arrest soot and ash. It furthermore arrests the draft of the furnace, so that combustion of inflammable elements in the fire-chamber and flues is greatly increased.

Having described my invention, I claim—

1. In a steam-boiler furnace, a laterally concave bridge-wall, the concave top of which forms a flue with the convex shell of the boiler, and the front surface of which forms an in-

clined and concave fire-bed at the rear part of the fire-box, substantially as specified.

2. The combination of the laterally-concave steam-injecting pipe, its side pipe-coil connections, its front pipe-connection located in the smoke-box, and a pipe provided with a cock and leading to water-vessel, substantially as described.

3. The combination, with the smoke-box, of a heat retainer composed of plates having curved edges and connected by bridges and a removable supporting-frame, substantially as and for the purposes described.

In testimony that I claim the foregoing as my own I affix my signature in presence of two witnesses.

JOSEPH P. TUTTLE.
